(57) **CLAIM**

The ornamental design for an amphibious aircraft hull, as shown and described.

DESCRIPTION

FIG. 1 is a bottom, right front perspective view of an amphibious aircraft hull showing our new design;

FIG. 2 is a bottom, left rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The structural elements depicted by broken lines have been shown for the purpose of illustrating environmental features that form no part of the claimed design.
